UNITED STATES PATENT OFFICE.

JOSEPH H. CHEEVER, OF SOMERVILLE, MASSACHUSETTS.

TELEPHONE.

SPECIFICATION forming part of Letters Patent No. 291,684, dated January 8, 1884.

Application filed February 15, 1883. (No model.)

To all whom it may concern.

Be it known that I, JOSEPH H. CHEEVER, of Somerville, in the county of Middlesex and State of Massachusetts, have invented certain 5 Improvements in Telephones, of which the following is a specification.

My invention relates to magneto-telephones, and has for its object the production of an instrument that will both transmit and receive 10 speech with great distinctness of articulation, and great volume.

The principal feature of this invention is the employment of two diaphragms, preferably of iron, these diaphragms forming one a common north pole-piece and the other a common south pole-piece for a number of magnets arranged radially around and connected with the diaphragms.

Referring to the drawings accompanying 20 this specification, Figure 1 is a rear view of the diaphragms, showing the magnets radiating therefrom. Fig. 2 is a sectional view, showing an electro-magnet attached to the diaphragms. Fig. 3 is a section of the entire 25 instrument.

A suitable wooden frame, F, has a mouth-piece, M, fitted therein. On the rear of the upright portion of the frame F is a recess, and covering this and fastened by its edges is 30 a diaphragm, D. This diaphragm is fastened to the frame with screws B, which, passing through the north ends of magnets N and through the diaphragm, serve to hold the magnets in contact with the diaphragm, and both to the wooden frame M. The magnets N S are curved or made U shape, and have their south ends, S, connected radially with a second diaphragm, I. Between these two 35 diaphragms, and of a thickness nearly equaling the space between the diaphragms, is a coil, C, of insulated copper or iron wire. This coil is made of large diameter relative to its thickness, and is nearly as wide as the diaphragms. The terminals of this coil are to be 40 connected with the line-circuit, in the usual manner.

In Fig. 1 there are eight permanent magnets, shown as connected radially around and with the edge of the diaphragms, but the number 45 may be increased to as many as can be secured to the diaphragms or there is room for.

In Fig. 2 a single electro-magnet is shown as being attached to the diaphragms.

Where great magnetic moment is desired in the pole-pieces or diaphragms, electro-magnets may be substituted for the permanent magnets, and connected with a battery or magneto-machine, in the manner well understood.

By arranging the magnets in the manner shown, a powerful magnetic field is produced in the vicinity of the coil, which may be increased to great strength by the use of large diaphragms and strong electro-magnets.

In speaking near to the mouth-piece both 65 diaphragms are set in vibration, although the rear one in a lesser degree. Its inductive effects are added to that of the front diaphragm, D, because, being of an opposite polarity to the diaphragm D and being on the opposite of the 70 coil, its inductive effect is similar in character to that of the diaphragm D; hence there is no neutralization, and the combined effects of both diaphragms are utilized.

The coil C is made of fine wire preferably, 75 as there is a large number of convolutions of wire exposed to the inductive action of the diaphragms by so making.

This telephone acts equally well as a receiver and transmitter, and when two are 80 connected together in circuit, speech uttered in one will set its diaphragms in vibration, causing alternating currents of electricity of an undulatory character, to be induced in the coil thereof, which currents, passing over the 85 connecting-wires to the second telephone, will cause the diaphragms in the latter to vibrate synchronously with the former, thus reproducing the speech uttered.

I am aware that telephones have been made 90 with diaphragms charged so as to be of a north polarity on one face and a south polarity on the other; also, that a diaphragm has been made having magnets the north ends of which are united, so as to form a pole-piece 95 for a coil of wire, and the south ends placed near to or in contact with the diaphragm.

I do not claim, broadly, the charged diaphragm.

I claim—

In a telephone, the combination, with two diaphragms one of which constitutes a common

north pole-piece and the other a common south pole-piece of a number of electro or permanent magnets, of a coil of insulated wire placed between said diaphragms or pole-
5 pieces, and to be included in the line-circuit, substantially as and for the purpose described.

In testimony whereof I have signed my name,

in the presence of two subscribing witnesses, this 13th day of February, 1883.

JOSEPH H. CHEEVER.
